United States Patent

Des. 236,798
Patented Sept. 16, 1975

236,798

POST ANCHOR

Wayne F. Hall, 2911 Bankers Drive,
Bloomington, Ind. 47401

Filed Sept. 10, 1973, Ser. No. 395,956

Term of patent 14 years

Int. Cl. D8—08

U.S. Cl. D8—234

Fig. 1

Fig. 2

Fig. 3

Fig. 4

FIG. 1 is a top plan view of a post anchor, showing my new design.

FIG. 2 is a left hand side view thereof.

FIG. 3 is a front end view thereof.

FIG. 4 is a rear end view thereof.

The side opposite FIG. 2 is a mirror image of the side there shown.

The view of the bottom opposite that shown in FIG. 1 is a mirror image of the top as shown.

I claim:

The ornamental design for a post anchor, as shown and described.
